DEVICE FOR PRODUCING TOBACCO PORTIONS OF UNIFORM SIZE

Application filed October 20, 1923, Serial No. 669,803, and in Sweden May 4, 1923.

The present invention relates to such devices for equalizing tobacco portions of approximately the same size, in which a plurality of such tobacco portions are pressed together in a casing to form a single volume which is then divided into portions all of the same volume.

The present device is essentially characterized by the following arrangement:

10 The casing for receiving the original portions and the piston fitted therein are arranged so as to press together the portions to a certain volume in the casing by a vertical movement of the piston relatively to the casing, the latter being provided with a lateral opening serving as inlet for the tobacco portions and located at a lower height than the piston, when this latter is in its upper starting position.

20 The most important technical advantage of the invention is that the original tobacco portions, previously to their supply into the casing, did not need and may not be pressed or shaped in any way. The portions fall by 25 gravity through the supply opening into the casing, so that the different tobacco blades or blade parts of each supplied portion are uniformly distributed over the surface of the tobacco mass formed by the portions which 30 before have been supplied to and are contained in the casing.

Thus by utilizing the invention it is possible to employ devices for obtaining the original portions which are very simple in construction and thus cheap in manufacture.

The invention is illustrated in the accompanying drawings in which:

Figure 1 is a front view of one form of embodiment, adapted for forming cigar and 40 cigar-cigarette-filler portions.

Figure 2 is a section along the line A—A and

Figure 3 is a section along the line B—B of Fig. 1.

45 Figures 4 and 5 show the apparatus in two different working positions.

Figure 6 is a vertical section of a form of embodiment, adapted for uncut long filler tobacco.

50 Figure 7 is an end view of Figure 1.

Figure 8 is a vertical section on line C—C of Figure 1.

In the drawings 1 and 2 indicate the front and rear walls respectively of a vertical casing and 3 and 4 indicate the small lateral walls thereof respectively. In horizontal section the casing has an outline corresponding to the desired outline of the roll filler to be produced, and is open at the top and bottom. The said casing is provided with an opening in the wall 1, said opening communicating with a funnel 5. Inserted through the top opening of the casing is a piston 6, the cross-section of which corresponds to that of the casing so that the piston will fit exactly 60 into the interior of the casing. Figs. 2 and 3. Projecting from the lateral walls 3 and 4 of the casing are journals 7 and 8, and on each of said journals a double-armed lever 9, 10 is mounted. The arms 10 of the lever 9, 10 have toothed segments or curved racks 10^a at the upper free ends, and said curved racks engage similar racks 11^a on arms 11 secured to a horizontal shaft 21 rotatable in bearings 20 on a slide 14. Secured to the lower ends 65 of the downwardly directed arms of the levers 9, 10 is a cutter 12. The lateral walls 3 and 4 of the casing are provided with outwardly directed projections 13, forming ears for screws or the like, by which the casing is secured to the slide 14 running on vertical guides 15, which, are connected with each other at the top by means of the cross-piece 17 carrying the piston 6, and which are in turn slidable in vertical guides in the table 16. 70

The slide 14 receives its reciprocating motion by means of rods 18 engaging journals 19 on the slide and being moved up and down in the desired manner by means of any suitable device. The guides 15 with the cross 75 piece 17 are moved up and down by any suitable device in such manner that the piston 6 connected to the cross piece 17 receives a reciprocating movement vertically. Connected to one end of the shaft 21 is one end of an arm 22, the other end of which is pivotally connected to a rod 23 reciprocated by any suitable mechanism in such manner that the cutter 12 through the parts 21, 11, 10, 9 receives a swinging movement. 80

The parts being in the position shown in Fig. 2, in which the piston 6 occupies an upper position and the casing is filled with a mass of tobacco equivalent to a certain number or portions of filler tobacco, introduced through the funnel 5, the manner of operation is as follows. Before the piston moves down, a further portion of filler tobacco is fed into the casing, which will then be filled about 10 to the line 25. At that time the casing and the piston receive a downward movement, and before the casing has reached its lower position the cutter 12, which has hitherto formed the bottom of the casing, is swung from the 15 position shown in Fig. 2 to that shown in Fig. 4, thereby opening the lower end of the casing.

The piston then moves down relatively to the casing to a certain level so as to press 20 together the tobacco mass to a certain predetermined volume against the table 16. While the piston remains in its said lower position, the casing 1, 2, 3, 4 moves upwards to the position shown in Fig. 5 carrying the cutter 25 with it, which latter, however, during this movement remains in its swung out position, so that from the tobacco mass formed by the tobacco portions pressed together a part, corresponding to that required for a roll, will 30 be clear of the casing at the bottom and rest on the table. As soon as the position shown in Fig. 5 has been reached, the cutter 12 is 35 swung inwards and cuts off the said free portion of the tobacco mass and again forms the bottom of the casing. Then, the casing 1, 2, 3, 4 and the piston 6 return to the position shown in Fig. 2 and the cut off filler tobacco will be rolled into a wrapper in a suitable manner (not shown) the described operation 40 being, then, repeated.

In order that the tobacco shall not make any resistance when moving down through the casing or tend to raise with the piston, after the portions have been pressed together, 45 the casing preferably widens in the downward direction.

The principle of operation of the embodiment of the invention above described is as follows: after a certain number of portions, 50 for instance, of filler tobacco have been introduced and pressed together in the casing, an additional portion is introduced, and, the piston then presses together all portions to a volume which is always constant, from 55 which a constant fraction in the present case 1/7, is cut off. If, then for example, the last introduced portion were only $\frac{3}{4}$ of a normal portion while the other portions, were however, practically normal, the total volume obtained will be $6\frac{3}{4}$ portions, from which 1/7th i. e., $6\frac{3}{4} \times \frac{1}{7} = 0.965$ of a normal portion will be cut off.

If one or more of the first portions were of somewhat greater volume than the normal 65 portion, the cut off part, obviously, is of a

volume, which still more nearly approaches the normal portion. As it is not possible in hitherto known devices for portioning filler tobacco for rolls to feed such small portions as are required for a single roll, without the several portions varying to a considerable extent, while, on the other hand, the sum of a larger number of portions, for instance, 5 or 6, will, practically, always be constant, it is easily seen that the invention, by which such an equalization of the portions is obtained so that all portions will, practically, be equal in volume, involves considerable technical advantages.

When the invention is adapted for manufacturing rolls using long filler tobacco, the form of embodiment shown in Fig. 6 is, preferably, used.

In this case, the filler tobacco used for the rolls is fed from above the casing and between two walls 26 applied to the casing, which, if desired may in known manner form reciprocating gripping members feeding the fillers.

When the piston 6 moves down from the position shown in Figure 6, the tobacco portions placed between the walls 26 will by means of the piston be fed down into the casing. Then, subsequent operation will be exactly analogous with that described with reference to Figs. 1 to 5.

Obviously, the invention may be carried out in other manner than that described and shown. Thus, after a certain number, for instance, 7 portions have been reduced to a certain volume, said volume may immediately be divided into seven equal parts, and, then seven new portions are brought together, before the next division is performed.

This can, for instance, be effected in the following way:—

In the position shown in Fig. 2 the casing is filled with the predetermined number, for instance, seven, portions. Then the casing, piston and knife are moved to the position shown in Fig. 4, whereupon the piston moves down to a certain position so as to press together the seven portions to a certain volume.

Then the casing moves upwards to the position of Fig. 5, whereafter the uncovered lower part of the mass is cut off by the knife and removed. Then the knife uncovers the outlet opening of the casing, whereupon the piston by means of a cam disc or any other known means, moves down further to an extent corresponding to the height of the cut off and removed tobacco portion, so as to move the under surface of the remaining mass in the casing into contact with the latch 16. The knife is now again swung inward so as to cut off the lower uncovered part of the mass. This operation is repeated until the casing is empty. Finally the parts are brought to the original position, shown in Fig. 2, the empty casing receiving again seven portions which are pressed together and so on.

Further, the portions fed into the casing may be so large as to be each sufficient for, for instance, two rolls in which case the tobacco volume obtained, obviously, has to be divided into twice as many parts as the number of portions which have been fed into the casing. The parts are then moved to the position of Fig. 4, the greater portions fed being compressed by the piston to a certain volume, which is then cut into equal portions as described above, the piston being moved further down after each cutting operation to an extent corresponding to the height of the cut off and removed tobacco portion. When the casing is emptied, the parts are returned to the position in Fig. 2.

The fed portions may also be smaller than the filler of a roll, for instance half of it, and in this case the volume obtained has, obviously, to be divided into a number of parts which is just half of the number of the smaller portions simultaneously brought together into the casing.

Preferably, the apparatus may be combined with a tobacco machine, a so-called tobacco feeder, of the type which feeds the tobacco by portions, the combination being preferably such a one that the portions fed from the tobacco feeder will automatically enter the casing. However, the tobacco portions, which are to be fed into the casing, may also be proportioned by other means or manually.

It is evident that, in case of the casing containing a volume corresponding to a plurality of portions, the piston has to be moved further down after each cutting operation to an extent corresponding to the height of the cut off and removed tobacco portion, so as to bring the under surface of the remaining mass in the casing into contact with the table 16. The means for imparting such movement to the piston may, evidently, be of any known kind, for instance a cam disc or the like.

If the height of the portions to be cut off is predetermined, which obviously is the case in making rolls of a certain size, the movements of the casing away from the table 16 always remain constant independent of the number and size of the portions fed into the casing and also the downward movements of the piston after each cutting operation remains constant, i. e., the piston moves down after each cutting operation through a distance corresponding to the height of the cut off portions, so that, before the next cutting operation takes place, the remaining mass in the casing will always abut against the table 16.

What we claim as new and desire to secure by Letters Patent is:—

1. In a device for producing tobacco portions of approximately the same size, the combination of a bed, an open ended casing for receiving the tobacco, a piston reciprocating in said casing for compressing the tobacco, a knife for dividing the tobacco

volume contained in the casing, said knife being mounted to swing below the lower end of the casing to close the same, means for simultaneously moving the casing and piston vertically from an upper position downward to move the casing to within a short distance of the bed, means for causing the knife to swing outwardly from under the casing, means for causing the piston after the casing has reached its lower limit position to move further downwards relatively to the casing, so that the tobacco portions will be brought together to a certain volume between the piston and the bed, and means whereby after the casing has moved a small distance in the upward direction the knife is swung inwardly and cuts off that part of the tobacco volume which is made free by the upward movement of the casing.

2. In a device for producing tobacco portions of approximately the same size, the combination of a vertically movable frame, a casing for receiving the tobacco, a piston reciprocating in said casing for compressing the tobacco, means whereby a portion of the tobacco will project from the casing, a knife for cutting off the projecting portion of tobacco, the casing and piston being movable vertically, two arms secured to the ends of the knife and pivotally connected to the side walls of the casing, one end of the arms being provided with curved racks, a shaft rotatably mounted on the movable frame, arms mounted on the shaft and provided with racks engaging the racks of the first-mentioned arms.

3. In a device for producing tobacco portions of the same size, a vertically movable casing into which the tobacco is fed, a knife pivotally mounted to swing below the lower end of the casing to form a bottom therefore, and a piston in the casing for compressing the tobacco therein.

4. In a device for producing tobacco portions of the same size, a table, a vertically movable casing above the table and into which the tobacco is fed, a piston in the casing for compressing the tobacco in the casing onto the table, means for raising the casing to leave a portion of the tobacco projecting from the casing, and a knife for cutting off the projecting portion of tobacco.

5. In a device for producing tobacco portions of the same size, a table, a vertically movable casing above the table and into which the tobacco is fed, a pivotally mounted knife normally below the lower end of the casing and forming a bottom therefore, a piston in the casing, means for lowering the casing and piston, means for swinging the knife from under the casing before it has reached its lowermost position, means for lowering the piston to press the tobacco onto the table, means for raising the casing to leave a portion of the tobacco projecting from the casing, and means for swinging the

knife under the casing to cut off the projecting portion of tobacco.

6. A device for producing tobacco portions of the same size, comprising a table, a vertically movable casing above the table and into which the tobacco is fed, means for raising and lowering the casing, a piston in the casing, means for reciprocating the piston to compressing the tobacco in the casing onto the table when the casing is in its lowermost position, a movably mounted knife, and means for operating the knife, the movements of the casing, piston and knife being so timed that when the casing and piston have been moved to their lowermost position, the casing will be raised to leave a portion of the tobacco projecting therefrom and resting upon the table, and the knife operated to cut off the said projecting portion of tobacco.

7. A device for producing tobacco portions of the same size, comprising a table, a vertically movable casing above the table and into which the tobacco is fed, means for raising and lowering the casing, a piston in the casing, means for reciprocating the piston, to compress the tobacco in the casing, and force it into engagement with the table when the casing is in its lowermost position, a knife pivotally mounted on the casing and serving when the tobacco is compressed in the casing as a bottom for said casing and means for operating the knife, the movements of the casing, piston and knife being so timed that when the piston is in its lowermost position, the casing will be raised to leave a portion of the tobacco projecting therefrom and resting upon the table, and the knife swung under the lower end of the casing to cut off the projecting portion of tobacco.

In testimony whereof we affix our signatures.
